[57] CLAIM

The ornamental design for a combined bidet, bidet control, toilet seat and cover, as shown and described.

DESCRIPTION

FIG. 1 is a front elevational view a combined bidet, bidet control, toilet seat and cover showing my new design;

FIG. 2 is a rear elevational view thereof;

FIG. 3 is a left side elevational view thereof;

FIG. 4 is a right side elevational view thereof;

FIG. 5 is a top view thereof;

FIG. 6 is a bottom view thereof; and,

FIG. 7 is a perspective view taken from the top, front and left side thereof, with the cover in a raised position and showing the bidet control and bidet.

The broken line representation of a toilet in FIG. 7 is for purposes of illustration only and forms no part of the claimed design.

FIG. 1

FIG. 2

FIG. 3

FIG. 4

FIG. 5

FIG. 6

FIG. 7
